UNITED STATES PATENT OFFICE.

HENRY G. GUILD, OF NEW YORK, N. Y.

COMB.

SPECIFICATION forming part of Letters Patent No. 399,032, dated March 5, 1889.

Application filed July 20, 1887. Serial No. 244,797. (No model.)

To all whom it may concern:

Be it known that I, HENRY G. GUILD, a citizen of the United States, and a resident of the city, county, and State of New York, have invented certain new and useful Improvements in Combs and their Manufacture, of which the following is a specification.

My invention relates to toilet-combs with independent teeth, or teeth not integral with the comb-head, and to the manufacture of combs of this character.

The object of my invention is, in the main, to provide an improved method of securing the metal teeth in the sheet-metal head; but its object is also to provide guard-teeth formed integrally with the head, all as will be hereinafter set forth.

My invention will be fully described hereinafter, and its novel features carefully defined in the claims.

In the drawings which serve to illustrate my invention, Figures 1, 1^a, and 1^b illustrate the blank of sheet metal destined to form the comb-head and integral guard-teeth. Fig. 1 is a plan, and Fig. 1^a an end, view of the plate cut to form the head, and Fig. 1^b is an end view of said plate after it has been folded. Fig. 2 is a view of the finished comb; and Fig. 3 is a transverse section of same, taken in the plane of one of the teeth. Figs. 4 and 4^a are views on a large scale, designed to illustrate the manner in which the metal head is pressed in between and around the teeth. Fig. 5 is an elevation, and Fig. 6 is a transverse section, illustrating a slight variation in the construction of the comb, that will be hereinafter explained; and Fig. 7 is a detached view, on a larger scale, illustrating the perforated trough-like strip used in the construction illustrated in Figs. 5 and 6. Figs. 8, 8^a, and 8^b illustrate a modification of my invention where the head of the comb is formed of two pieces or parts, and Figs. 9 and 9^a show a cross-section of a comb so formed with a binding-strip on the head.

The blank for the comb-head (seen in Fig. 1) compresses the head proper, *a*, which is folded along its middle to embrace the ends of the wire teeth *b b*, and the prongs *a^x a^x* at its ends, which fold together face to face and

are soldered together, to form the guard-teeth. In carrying out my invention I prefer to, and generally do, proceed as follows:

I cut the blank for the comb-head of the form shown in Fig. 1 from sheet metal and apply solder to one of its faces, or "tin" it. The solder is represented by the dotted line in Figs. 1^a and 1^b. I then fold this blank lengthwise along the line *xx* in Fig. 1, which gives the blank somewhat the appearance seen in Fig. 1^b. I now place the teeth between the plies of the folded head *a*, spacing them properly, and then submit the head to pressure which swages the metal of the plies of the head in between the teeth until the two "tinmed" faces thereof meet and embed the teeth firmly in the metal of the head. The prongs *a^x a^x* are also brought together by the pressure until their tinned faces meet and are pressed firmly together. Heat sufficient to melt the solder is now applied and the comb allowed to cool. It will then be found that the teeth *b b* are rigidly and permanently fixed in the head, and that the pairs of prongs *a^x* will be joined two-and-two in a substantially integral manner, each two prongs forming a guard-tooth, *b^x*, having twice the thickness of the plate from which the prongs are formed.

In pressing the head I may, and usually do, form a tubular stiffening-rib, *a'*, along the upper edge of the comb. Where the metal of the comb-head is quite thin relatively to the thickness of the teeth, I prefer to press the metal of the head in between the teeth, as represented in Figs. 2 and 4; but where the metal of the head has sufficient thickness relatively to the teeth to warrant it I may, and usually do, simply press down the head with a flat-faced die, so that the teeth embed themselves wholly in the mass of the metal, as represented in Fig. 4^a. In either case the faces of the plies of the folded head are brought tightly together between the teeth.

Figs. 5, 6, and 7 illustrate a slightly-different construction. In this mode of manufacture I make the head of precisely the same form as that seen in Fig. 1; but I form, also, a trough-like strip, *a²*, of sheet metal, provided with perforations (*a³* in Fig. 7) in its bottom

for the teeth. The teeth b are inserted in the perforations and the strip a^2 is placed between the plies of the head. The whole is then submitted to pressure and heated to melt the solder, as above described. A coating of solder may be applied to the outer faces of that portion of strip a^2 that is embraced between the plies of the head in order to effect a perfect joining of the two.

- 10 The teeth should have heads, or be roughened at their attached ends, or have a staple-like form. They may be of round wire, or be of square, angular, or flattened forms. I prefer round wire.
- 15 I do not limit myself to tinning or applying solder to the head for the purpose of securing the teeth b therein. The prongs a^x to form the guard-teeth must, however, be soldered rigidly together; but this may be effected 20 after the pressing, though not so conveniently nor so well.

It is not absolutely essential that the blank for the head should be formed in one piece and bent to the form seen in Fig. 1^b. The 25 said blank may be in two like parts, as would be represented by cutting the blank seen in Fig. 1 along the line x x . This is represented in Figs. 8, 8^a, and 8^b. The latter figure represents the two like parts or sections placed 30 face to face.

When the comb-head is constructed of two sections in this manner, I may, and usually do, apply a sheet-metal re-enforce or binding strip, c , thereto, as represented in Figs. 9 and 35 9^a, to cover the joint at the back of the head and add stiffness to the latter.

In Figs. 1 and 8 a few of the teeth are represented in dotted lines merely to show the position they are designed to occupy with respect to the blank.

I may say that in carrying out my invention I space, hold, and arrange the teeth b by clamping them between plates or dies, the attaching ends being exposed, so that the head may be placed thereon and swaged down; but 45 this mode of holding the teeth is not new in the manufacture of combs.

Having thus described my invention, I claim—

1. The herein-described method of making 50 toilet-combs, which consists in first forming the blank for the head of the comb of sheet metal with integral prongs a^x a^x , then applying a film of solder to the one face of each of said prongs, then placing the metal teeth of the comb between the plies of the head and subjecting the whole to pressure, as described, then heating the comb until the solder melts, and then cooling it, substantially as set forth.

2. A comb having its head and guard-teeth 55 formed of two thicknesses or plies of sheet metal of like form, placed face to face and soldered together, substantially as set forth.

3. A comb having its head and guard-teeth formed of a sheet-metal blank comprising the 60 body a and four prongs, a^x a^x , said blank being folded along the line x , and the prongs a^x a^x thus brought face to face in pairs united by solder to form the guard-teeth b^x , substantially as set forth.

In witness whereof I have hereunto signed my name in the presence of two subscribing witnesses.

HENRY G. GUILD.
